LIGHTNING ARRESTER

Application filed April 21, 1924. Serial No. 707,843.

My invention relates to lightning arresters and it has particular relation to spark-gap devices used in such arresters.

One object of my invention is to provide a lightning arrester which shall have a high discharge capacity for lightning and surges and which shall produce the smallest possible disturbance on the circuit which is to be protected.

10 Another object of my invention is to provide a lightning arrester having a relatively large discharge capacity for surges and overvoltages and a very low discharge capacity for voltages of the order of the normal line 15 voltage.

Another object of my invention is to provide an improved resistance material having directional conductivity for making my improved lightning arrester.

20 A still further object of my invention is to provide a new method of making resistor materials of the above described character.

In making my improved arrester, I employ 25 a gap electrode having directional conductivity, that is, being capable of conducting electricity in the direction of the discharge path between the gap electrodes but being almost an insulator in a direction transverse thereto. As a result, current passing through 30 the gap is subdivided into a large number of minute currents, each traversing the relatively high resistance of the individual paths and requiring a relatively high voltage across 35 the gap electrodes for maintaining the same.

By properly proportioning the voltage necessary to maintain such current through the 40 gaps of the arrester and the operating voltage of the line, I am able to prevent the passage of material amounts of currents at line 45 voltage while presenting a discharge path of relatively low resistance for voltages substantially above the line voltage.

With the foregoing and other objects in 45 view, my invention comprises the arrangements, details of construction and processes described and claimed hereinafter and illustrated in the accompanying drawing, wherein

50 Figure 1 is a sectional view of a lightning arrester made according to my invention,

Fig. 2 is a similar view of a modification of my invention,

Fig. 3 is a view in section of another modification of my invention, and

Fig. 4 is a view in perspective illustrating 55 the principle of the pencil-like structure of the resistance plates employed in my invention.

Referring to Fig. 1, the lightning arrester comprises a cylindrical porcelain casing 1 60 having mounted therein a plurality of parallel resistance plates 2 which are spaced from each other by mica spacers or rings 16 of about three mils thickness, as subsequently described, providing minute gaps 3 which are shown exaggerated in size, for the sake of illustration. The stack of plates 2 is held between two terminal plates 4 and 5 of conducting material such as copper. The upper terminal plate 5 constitutes one electrode of 65 an auxiliary gap device 6 connected in series with the stack of resistance plates 2, the other terminal 7 of the auxiliary gap device leading to a terminal lead 8. The lower terminal plate 4 is connected to another terminal lead 70 75 9 which passes through an opening 10 in the lower portion of the casing. The two electrodes 5 and 7 of the series gap device 6 are held in spaced relation by a porcelain ring 12. The auxiliary gap device and the stack 80 of plates are held in place by means of a clamping spring 13 and a cap 14 inclosing the upper side of the porcelain casing 1 and secured thereto by pitch or a similar bonding material which fills the space 15 between the 85 cap 14 and the casing.

The principal novel feature of my invention is the particular construction of the plates 2 and the mode in which the same are manufactured and assembled in the arrester. 90 It is well known that when an electric current passes through a gap between two electrodes, the character of the discharge is entirely different when the current through the gap is small, of the order of a fraction of an ampere, than in the case where the current has a value of the order of amperes or more. In the latter case the voltage required to maintain a current between the two electrodes is low and an increase of the current 95 100

tends to lower the voltage of the discharge. The principal reasons for this phenomenon are that the current generates sufficient heat near the terminal of the discharge, at the 5 surface of the electrodes, to maintain the same in an incandescent state replenishing the electrons and ions necessary to carry the current through the space between the electrodes. Thus, an increase in the current in- 10 creases the ionization of the space between the gap electrodes and consequently a lower voltage is sufficient to pass larger currents. However, when the current between the electrodes is sufficiently low to avoid the heating 15 of the terminals of the discharge upon the surface of the electrodes, there is not present a sufficient supply of electrons and ions to maintain the discharge at the low voltages of an ordinary arc and the discharge between 20 the electrodes takes the form of a glow discharge, the minimum voltage necessary for maintaining a discharge of such character being the voltage corresponding to the so-called "cathode drop" in the glow discharge. 25 According to my invention, the arrester has one or more gap devices, the individual gap devices being so designed as to practically force the current between the gap electrodes to take the form of a glow discharge, requiring 30 a high potential for maintaining the same and making actually impossible the formation of low-voltage arcs between the gap electrodes.

The plates 2, constituting the electrodes of 35 my improved lightning arrester, are made of a directionally conductive resistance material which will be described in detail hereinafter, said material having sufficient conductivity in the direction of the discharge between the 40 electrode surfaces, but having a resistance of the order of an insulating resistance in a direction transverse thereto. The individual electrode plates are preferably spaced from each other by spacers of insulating 45 material such as mica rings 16.

A good physical conception of the operation of a lightning arrester made according 50 to the foregoing description may be had by considering a gap device having an electrode plate, as shown diagrammatically in Fig. 4, formed by a multitude of pencil or filament-like resistance elements disposed in side by side relation and bonded by a suitable insulating material. Suppose that the resistance of 55 each pencil is 10,000 ohms and the breakdown voltage of the gap is 500 volts. When the voltage across the gap is gradually raised, a spark will pass to one pencil and because of the high resistance of the same, the current 60 therethrough will be limited to a small value, less than 50 milliamperes, in the case assumed. The voltage necessary to maintain such a current is relatively high and a reduction of the voltage considerably below the value of 500 65 volts will cause the discharge to become un-

stable and eventually interrupted. If the applied voltage is raised to a value higher than 500 volts, enormous currents will flow, since the multitude of individual gaps constituted by the terminals of the pencils and the opposite electrode surface will successively break down, each of the pencils carrying only a small current but requiring a definite minimum voltage in order to maintain the discharge. Taking, for instance, 50 milliamperes as the current in each pencil and 1,000 pencils per square inch, we get 50 amperes per square inch, and for a plate having a surface of 6 square inches a current of 300 amperes will discharge through the gap before the voltage is permitted to rise above approximately 500 volts.

In the practical construction of lightning arresters, certain additional refinements may be resorted to in order to make an arrester having good performance characteristics. Thus it is found that the extinction voltage, that is, the voltage at which the minute current between the two electrodes will stop, is approximately equal to the voltage of the 90 cathode drop in a glow discharge. The gaps are accordingly so constructed that the breakdown voltage thereof corresponds to the voltage of the cathode drop in a glow discharge. In practical applications of such construction, I may place an arrester, comprising a 95 gap or a plurality of series connected gaps, across a line having an operating voltage somewhat lower than the voltage of the cathode drop times the number of serially disposed gaps. With such construction, no discharge through the arrester will take place when the line is at the normal operating voltage, since such voltage is not sufficient to 100 maintain a discharge through the gaps. Any increase of the line potential causes a very free discharge through the arrester through the multitude of parallel paths until the potential across the line is lowered to the point at which the discharge stops, and which corresponds, in the above cited case, approximately to the line voltage.

In the practical operation of arresters, the relief voltage, or the voltage at which the arrester discharges freely, is ordinarily so chosen as to be 1½ to 2 times the normal line voltage, and an auxiliary or insulating gap arrester is disposed in series with the stack of disc-gaps in order to prevent the passage of small leakage currents through the arrester, which would produce unnecessary heating of the same under normal operating conditions. The small spacing of the gap elements makes it very difficult to secure a high leakage resistance for the minute gaps of the arrester, and accordingly, if the stack of plates is directly connected to the line, a small leakage current will pass therethrough at voltages of the order of the normal operating voltages.

In the practical embodiment of an arrester 130

employing a plurality of parallel plates constituting minute gap arresters, I employ a construction wherein the individual plates are beveled at their edges 17. The mica rings 16 separating the individual plates are of approximately the same diameter as the plates and about three mils thick. The entire stack of plates may, when assembled, be bonded with an insulating bonding mass 18, such as plaster of Paris or a proper mixture of water glass and an inert material which, when dry, holds the plates together. The beveled edges are instrumental in preventing lightning discharges, or in general any high-potential discharges, from flashing over the insulating spacer outside of the plate and eventually bridging over several of the plates and actually short-circuiting the same.

20 The end plates of the stack of discs of resistor material which make contact with the terminal plates 4 or 5 are so made as to prevent any sparking, which may be harmful to the arrester. I have found that if the 25 end plates are placed directly in contact with the metallic terminal plates, the end-plates are, for some unknown reason, shattered and broken after passing a large number of discharges.

30 A very good construction for making an intimate contact between the end plates and the terminal plates and avoiding the shattering of the end plates consists in coating the contacting surface of each end plate with 35 a layer 19 of conducting material such as graphite or, preferably, spraying thereon a layer of metal by means of the Schoop process, for instance. The metallic layer 19 is thus firmly united with the resistance plate 40 and makes intimate contact with the individual high-resistance paths extending therethrough.

In Fig. 2 is shown a modification of my invention wherein the individual gaps of the 45 arrester are formed by alternate plates 21 of resistor material and plates 22 of conducting material such as iron or brass, for instance. The close spacing of the individual gaps 23 is obtained by means of mica spacers 50 24 as in the case of the arrester illustrated in Fig. 1. The diameter of the resistor plates 21 is somewhat larger than the diameter of the plates 22 of conducting material. Such 55 construction is instrumental in reducing any possibilities of a flash-over between the individual metal plates 22 on account of the large path separating the same and the relatively low voltage gradient along the path. I regard the above-described construction as 60 a distinct feature of my invention.

Another modification of my invention is shown in Fig. 3 wherein each gap device constitutes an individual cell 26. Each gap cell 65 comprises a ring 27 of insulating material, such as porcelain, having mounted in the

inner portion thereof a resistance plate 28 having directional conductivity as described hereinbefore. The lower side of the resistor plate 28 is coated with a layer of metal 29 and is in electrical contact with a sheet-metal cover 30 having its outer edge bent and secured over an extending flange 31 of the porcelain ring 27. The other side of the resistance plate 28 constitutes the active gap surface cooperating with the surface of a metal cover 32 which is secured to the outer edge of the porcelain ring 27 in the same manner as the lower cover 30.

If desired, an arrester employing resistor plates having directional conductivity may 80 be effectively operated with gaps having a break-down voltage which is considerably above the voltage of the cathode drop in a glow discharge. If a lightning arrester made with a larger gap is placed across a line, the 85 operating voltage of which corresponds to approximately twice the line voltage but in which the minimum voltage required for maintaining a discharge through the arrester is somewhat below the operating voltage of the line, good performance and good protection will be secured without serious disturbances on the line, since the excess of line current which will pass through the arrester will be relatively small and the voltage for 90 maintaining the same will be sufficiently high to cause the discharge to stop when the current passes through zero at the next alternation.

A distinct feature of my present invention 100 is the process of making the directionally conducting resistance elements utilized in arresters of the above-described character. According to one method, I may obtain directionally conducting material having a 105 very high resistance for the passage of current in the direction transverse to the direction in which it is intended to be conducted by assembling filamentary threads of resistor material of the desired resistivity in side by side relation and bonding the same into a mechanically homogeneous mass. The body 110 so obtained is then cut in a direction transverse to the direction of the threads to produce electrode elements of the desired thickness. The threads may be bonded with any 115 suitable binder such as water glass or powdered kaolin, the binder serving also to insulate the individual threads from each other.

According to a preferred method of making the resistor plates from thread-like elements, I employ a thread made of a substance, such as cellulose, silk, or the like, which becomes carbonized when heated to a high temperature, and wind the same in side-by-side relation upon a reel or frame. The thread may be passed through a refractory bonding material such as clay before winding the same or the body of the wound threads may be 120 impregnated with the binding material after 125

winding. The plastic body of threads which is so formed may be cut into slabs or elements of desired thickness and may be fired until the threads are carbonized and the clay is entirely hardened. The hardening or firing process may take place either before or after the thread-like body is cut into the desired shape. The resulting blocks of the material consist of fine, parallel, carbonized conductors which are insulated from each other by the insulating clay bond.

If desired, the thread may be impregnated or filled with a substance, such as with india ink or a colloidal solution of graphite, tending to give the thread a higher conductivity when carbonized.

My invention is not restricted to the details and modifications described hereinbefore but may be carried out in many other ways without departing from the spirit thereof and I desire that the appended claims be awarded the broadest construction consistent with the prior art.

I claim as my invention:

25 1. A space-current device operating on the glow-discharge principle and comprising two electrodes, at least one electrode being made of material having a plurality of closely packed, parallel, directionally conducting filamentary resistor elements carrying the glow-discharge current and disposed in the direction of the discharge path between the two electrodes, said filamentary resistor elements extending the entire length of the electrode.

20 2. A space-current device comprising two closely spaced electrodes, at least one electrode being made of material having a relatively large conductivity in the direction of the discharge path between the two electrodes and having a relatively low conductivity in a direction transverse thereto, the spacing between the electrodes and the character of said electrode being such that a continuous, substantially evenly distributed discharge of the glow tube is produced and maintained over the cross-section of the discharge space throughout the continuance of a discharge.

25 3. A space-current device comprising two electrodes, at least one electrode being made of material having a plurality of parallel, directionally conducting paths disposed in the direction of the discharge path between the two electrodes, the resistance of the individual conducting paths being of such magnitude as to require a voltage of the order of the cathode drop in a glow discharge or more to maintain a current of a fraction of an ampere per path between the terminals thereof and the opposite electrode.

4. A lightning arrester comprising a gap device having at least one electrode comprising a plurality of parallel conducting paths disposed in the direction of discharge in the gap, the resistivity of the individual paths be-

ing relatively high and the resistivity between the individual paths in a transverse direction being so large as to substantially prevent passage of currents between one path and another, the number of conducting paths in said electrode being of the order of 10^2 per cm^2 , and the current discharge being of the order of amperes per cm^2 .

5. A lightning arrester comprising two parallel plate electrodes separated by a gap, at least one of said electrodes being of a resistor material having a resistivity of the order of one ohm per centimeter cube in the direction of the discharge path and having a resistivity of a multiple of the above named value in the direction transverse to the discharge path.

6. A lightning arrester having two parallel plate electrodes separated by a gap, at least one of said electrodes being of a resistor material having a relatively large conductivity in the direction of the discharge path between the two plates and having a relatively high resistivity in a direction transverse thereto, the discharge conditions being such that no portion of either of said electrodes is heated to a temperature of copious ionization, throughout the occurrence of a discharge.

7. A lightning arrester having two parallel plate electrodes separated by a gap, at least one of said electrodes being of a resistor material having a relatively large conductivity in the direction of the discharge path between the two gaps and having a relatively high resistance in a direction transverse thereto, the back side of said electrode having a layer of a highly conducting substance, united thereto.

8. A lightning arrester comprising two parallel plate electrodes separated by a gap, at least one of said electrodes being made of a resistor material comprising a plurality of high resistance paths separated from each other by a relatively insulating bonding material.

9. A lightning arrester comprising two parallel plate electrodes separated by a gap, at least one of said electrodes being made of a resistor material comprising a plurality of high resistance paths separated from each other by a relatively insulating bonding material, the outer side of said electrode being homogeneously united with a conducting layer.

10. A lightning arrester having a plurality of spaced electrodes comprising a plurality of bodies of non-vaporizing conducting resistor material having a relatively high specific resistance in one direction and a still higher specific resistance of the order of an insulating resistance in a direction transverse thereto, the spacing between the electrodes and the materials of said bodies being such as to insure a discharge in the form of a

glow throughout the operation of the arrester.

11. A lightning arrester comprising a plurality of bodies constituting gap elements, said bodies having a resistance of the order of 10 ohms per square inch of cross-sectional area for currents flowing in the direction of the discharge paths across the gaps, and a resistance of the order of an insulating material in a direction transverse thereto, the gap spacings and the materials being such that no portion of the arrester reaches a temperature of copious electron emission throughout the operation of the device.

12. A lightning arrester comprising a plurality of parallel plates constituting closely spaced, parallel gap elements, the individual plates having relatively large conductivity in the direction of the discharge path and a relatively high resistance in a direction transverse thereto, the spacing and other characteristics being such that the discharges are maintained in the form of glow discharges without the formation of an arc.

13. A lightning arrester comprising a plurality of parallel plates constituting closely spaced, parallel gap elements the individual plates being of a material having an extremely large number of closely packed, parallel directionally conducting filamentary resistor elements substantially insulated from each other.

14. A lightning arrester comprising a plurality of parallel plates constituting closely spaced, parallel gap elements the individual plates being of a material having an extremely large number of closely packed, parallel, directionally conducting filamentary resistor elements substantially insulated from each other, the resistance of each individual filamentary resistor element being more than 100 ohms.

15. A lightning arrester comprising a plurality of parallel plates constituting closely spaced parallel gap elements the individual plates being of a material having an extremely large number of closely packed, parallel directionally conducting filamentary resistor elements substantially insulated from each other, the resistivity of the plates in the direction of the discharge filamentary resistor element being more than 1 ohm per centimeter cube.

16. A lightning arrester comprising a plurality of parallel plates constituting closely spaced, parallel gap elements the individual plates being of a material having an extremely large number of closely packed, parallel, directionally conducting filamentary resistor elements substantially insulated from each other, the resistivity of the individual filamentary resistor elements being so large as to require a voltage of the order of the cathode drop in a glow discharge to maintain a current of a small fraction of an ampere per path between the opposite electrodes.

17. A lightning arrester comprising a plurality of parallel plates constituting closely spaced, parallel gap elements, the individual plates having relatively large conductivity in the direction of the discharge path and a relatively high resistance in a direction transverse thereto, the spacing of the individual gaps being such that the breakdown voltage of an individual gap is substantially equal to the voltage drop in the discharge passing through the gap.

In testimony whereof, I have hereunto subscribed my name this 16th day of April, 1924.
